BLADE CUTTER

Jens A. W. Madsen, Sioux City, Iowa

Application February 5, 1937, Serial No. 124,256

2 Claims. (Cl. 30—156)

My invention relates to a device for holding and securely retaining razor blades or other blades for cutting operations.

An object of my invention is to provide such a holder which will allow convenient insertion of the blade.

A further object of my invention is to provide means for automatically locking the blade in operative position when the device is open for use.

A further object of my invention is to provide means for causing positive retention of the blade along the greater part of its area so that it will not become dislodged or loosened during the cutting operation.

A further object of my invention is to provide a blade holding unit which collapses to a minimum size, and which can be manufactured at a very reasonable cost.

With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Figure 1 is a side elevation of the cutter in its open position.

Figure 2 is a plan view of the same.

Figure 3 is a sectional view taken medially along the longitudinal center of the device.

Figure 4 shows the device in its collapsed position.

Figure 5 is an enlarged detail of the pivoting and locking means, and

Figure 6 is a further enlarged detail of an elevation of Figure 5.

I have used the character 10 to designate generally the blade receiving member which includes the side walls 11 which are suitably spaced to receive the razor blade 12, and which side walls converge into the indentations 13 at the end thereof to form the end of the device.

The lower ribs 14 provide means for convenient grasping with the finger nails to open the device. The side walls 11 include the cut away portions 15 having the sloping edges 16, all of the edges of which are bevelled as at 17. The shoulder 18 (see Figure 3) is so positioned to overlie one lower edge of the blade as shown, this edge being represented by the character 19.

The casing 20 includes the side walls 21, and this casing is pivoted to the blade receiving member 10 through the medium of a hollow rivet 22 passing therethrough as shown. The casing 20

includes the integrally formed edge which terminates in the arcuate extension 24, which extension terminates at 25.

When the holder is collapsed together as shown in Figure 4, the shoulder 18 will strike the point 25, preventing further closing so that the edge 26 of the blade will not strike any metal portions. The tensioning and locking arrangement is shown more clearly in Figure 5.

The side walls 11 of the blade receiving member extend into the raised portions 27. The space 28 is made fairly large in order to secure a maximum tensioning effect. The portions 27 again merge into the parallel extensions 29, which extensions are indented very slightly from the level 10 of the portions 27. This indentation is very small in comparison with the space 28 for reasons to be explained. Similarly the side walls 21 in the casing 20 include the slightly depressed indentations 30 which merge with the further 15 parallel extensions 31.

Looking at the elevation as shown in Figure 6, the indentations 30 in the outer casing walls 21 include the arcuate lower portions 32, and similarly the portions 27, which are formed with 25 the side walls 11, include the arcuate lower portions 33.

The method of operation of the device will now be explained. Before inserting the blade, the outer casing 20 and the blade holding member 10 are placed approximately at 45 degrees as shown in Figure 6, the blade is then inserted freely between the side walls 11 and is then pushed over against the end 13 (see Figure 3) so that the portion 19 underlies the shoulder 35 18. Next the casing 20 is opened to its extended position as shown in Figures 1, 2, and 3. During the extending operation, by virtue of the pivoting action on the rivet 22, the portions 30 will first come in contact against the raised portions 40 27 as shown clearly in Figure 6. As the portions 30 slide over the portions 27, compression will occur against the sides 11, thereby efficiently compressing the blade 12 along practically the entire area of the side walls 11. As soon as 45 the device is completely opened, the various projections and the like will take the position as shown in Figure 5. The portions 30 will then snap into the very slightly indented extension at 29. The reason for this is to insure that the 50 device is retained in its opened position during the cutting operation.

It will be noted, however, that the indentation at 29 is so slight that it merely holds the members open, and yet allows a maximum amount 55

of compression against the side walls 11 to retain the blade properly. This feature will be present since the spacing at 28 is considerably greater, being practically five times as great as the indentation at 29.

5 It is a simple matter to reverse this process allowing loosening of the blade so the same can be removed for replacement, etc.

The side walls 11 of the blade receiving member can be bowed inwardly in the shape of concave arcs to insure maximum tension against the center of the blade if so desired.

10 When folded together, the device appears as in Figure 4, which provides a convenient guard 15 and reduces the size of the device to a minimum.

15 The slight shoulders at 34 and 35 are provided to insure a maximum limited opening of the device. It will now be seen that I have provided a blade holder or cutter which allows convenient insertion of a blade, which automatically 20 locks the blade in operative position when the holder is open for use, which causes positive retention of the blade along a maximum compression area, which collapses to a minimum 25 size, and which can be manufactured at a very reasonable cost.

Some changes may be made in the construction 30 and arrangement of the parts of my invention without departing from the real spirit and purpose of my invention, and it is my intention to cover by my claims any modified forms of structure or use of mechanical equivalents, which may be reasonably included within their scope.

I claim as my invention:

35 1. A blade cutting device comprising an enclosed blade receiving member including spaced side walls and having an upper opening, an end shoulder for retaining a projecting edge of the blade, an outer casing pivoted to said blade receiving member, means for compressing said 40 blade receiving member side walls against the blade during opening movement of the casing

including oppositely indented portions in said side walls, said outer casing walls arranged to 5 coact therewith during said opening movement, the direction of movement of said casing walls being in the same plane as the blade and the blade receiving member, said receiving member side walls having major outwardly indented portions, said casing having minor inwardly indented portions against which said major portions compress during movement of the casing, 10 said major indentations in said side walls merging with the minor indentations to receive the same therein when the casing is fully opened to provide retention means.

2. A blade cutting device comprising an enclosed blade receiving member including spaced side walls and having an upper opening, an end shoulder for retaining a projecting edge of the blade, an outer casing pivoted to said blade receiving member, means for compressing said blade receiving member side walls against the blade during opening movement of the casing, 15 including oppositely indented portions in said side walls, said outer casing walls arranged to coact therewith during said opening movement, the direction of movement of said casing walls being in the same plane as the blade and the blade receiving member, said receiving member side walls having major outwardly indented portions, said casing having minor inwardly indented portions against which said major portions compress during movement of the casing, 20 said major indentations in said side walls merging with the minor indentations to receive the same therein when the casing is fully opened to provide retention means, said casing including an inwardly bent lip at the end thereof to 25 provide limiting movement of the casing with respect to the blade receiving member to prevent 30 injury to a blade edge.

35 JENS A. W. MADSEN.
